THERMAL AND MAGNETIC MEANS OF INDICATING TEMPERATURE AND ELECTRIC FAILURE

John N. MacInnes, Newfields, and Paul H. Gerard,
Newmarket, N. H.

Application February 12, 1951, Serial No. 210,565

2 Claims. (Cl. 340—227)

1

This invention relates generally to the class of electric signaling and is directed particularly to a system for use in connection with building heating and temperature indicating apparatus.

The object of the present invention is to provide a means of indicating temperature change and electric failure in connection with heating apparatus, such as oil burners, to give notice of the failure of electric current controlling the operation of such apparatus and/or the dropping of the building temperature below a desired level.

Another object of the invention is to provide a signal system of the character stated with means therein for energizing a signal in the event of overheating of the heating apparatus.

It is also an object of the invention to provide means for accomplishing the stated results, embodying two signals one of which is active when the heating equipment is operating properly and the temperature is correct, the other signal coming into operation and the first becoming inactive when the reverse conditions prevail.

The present application is a continuation-in-part of our pending application Serial No. 145,324, filed February 21, 1950.

The invention will be best understood from a consideration of the following detailed description taken in connection with the accompanying drawing wherein the single figure is a diagrammatic layout of the electrical system constituting the invention.

Referring now more particularly to the drawing the reference character 18 generally designates a portion of an outside wall of a building.

Exteriorly of the building is located, upon the wall or in any suitable location, a suitable receptacle 12, in which are mounted, to be clearly seen, the two signal lights 14 and 16, which are preferably, respectively red and green.

Within the building, as at 18, is a two circuit controlling electric relay, generally designated 20. This relay comprises the two circuit controlling armatures 22 and 24 both of which are under the control of an electromagnet coil 26.

The numeral 28 designates a conductor forming one side of an electric circuit drawing current from the low voltage side of the heating equipment. The most convenient source of such low voltage is the stack control of the burner. Such stack control has such low voltage current available as long as the burner is functioning properly and the power supply is not impaired. Since such stack control is standard equipment used on all automatically controlled and fired heating systems, it is not thought that illustra-

2

tion or further description of the same is necessary. This conductor is connected to one side of a thermostatic switch 30 which is within the building and closed at room temperature, the other side of which is connected to one side of the coil 26 by conductor 31. The other side of the coil is connected by conductor 32 to the return conductor 33 of the low voltage supply source, which conductor is also connected to one side of the green signal bulb 16.

The armature 24 of the relay is electrically connected by conductor 34 with the current supply line 28, and when the coil 26 is energized the armature 24 will be shifted to close the contacts 35 to complete the circuit for the bulb 16 through the conductor 36.

The numeral 38 designates a source of electric potential, one side of which is electrically connected by the conductor 39 with one side of the red signal light 14.

The other side of the light 14 is connected by conductor 40 with one of the two contacts 41, the other one of which is carried by the armature 22.

The numeral 42 designates a normally closed thermal switch, comprising a bimetallic strip 43 carrying one of two contacts 44, the other one of which is connected by the conductor 45, with the other side of the current source 38.

The bimetallic strip 43 is electrically connected by the conductor 46 with the red signal circuit closing armature 22.

In the operation of the system, in the event of power failure, overheating, failure to ignite properly, very poor combustion, or any other fault that might cause the stack control to "cut-out," the low voltage current supplied by the circuit conductors 28—32, is shut off. When the supply of low voltage current is shut off, light 16 is extinguished and magnet 23 is deenergized allowing points 41 to close thus completing the circuit of lines 46 and 39, causing light 14 to become energized and giving warning of the condition that exists. This action would accomplish all that is desired except for the fact that in the majority of heating installations the radiation is inadequate to take care of the output of the furnace. This brings about an overheating condition which is prevented from becoming dangerous by a limit control, not illustrated, which is a part of the standard oil burner circuit. When such overheating condition occurs the limit control shuts off the burner by cutting off the power supply to the stack control, thus shutting off the lower voltage supply. When this latter action occurs 55 the reaction, as far as the present signal device

is concerned, will be the same as a burner failure in that the green light 16 will go out and the red light 14 will come on. This, however, is undesirable inasmuch as overheating is a common occurrence and is not considered dangerous and will correct itself as soon as the furnace cools off a predetermined amount.

To eliminate the possibility of "false alarms" which would result from the overheating condition, thermal element 42 is installed on or near a heat convector so that, in the event of overheating, the bimetallic element 43 will open contacts 44 and will prevent a complete circuit from becoming established in the circuit 46-39, so that light 14 cannot give a false alarm. Thus in the event of overheating, green light 16 will go out, but red light 14 will not light due to the action of thermal element 42. Thus if circuit 46-39 is rendered incomplete by either, or both, the action of thermal element 42 or the armature 20, the light 14 will not be energized.

If the low voltage supply from the stack control on circuit 28-33 is shut off due to the stack control "cutting out," as a result of a faulty burner, or is shut off due to power line failure, the convector which unit 42 is on or near, will be relatively cool and thus the bimetallic element 43 will allow contacts 44 to remain closed, thus action of armature 20 will complete the circuit to energize light 14, which is proper.

The stack control, hereinbefore referred to is a standard unit as previously stated which is commonly used on all automatically controlled and fired heating systems. All of these stack controls embody a 24 volt supply which is derived from a transformer with which said stack controls are normally equipped. In the present invention the stack control serves only as a source of current supply to actuate the present invention. The invention itself does not in any way affect the operation of the stack control.

The invention has been thus far described in connection with its use with heating equipment employing a stack control unit but it is also designed for use with automatic gas fired heaters and when so employed the circuit wires 28-33 would be connected to the solenoid valve circuit inasmuch as most gas fired heating units are not equipped with stack controls.

We claim:

1. Means for indicating current failure in a principal electric circuit, comprising an electric

signal element connected in series in said circuit, a relay including a magnet coil and two parallel conductors movable as a unit between a first position in which the unit is held by the energized coil and a second position, one of said conductors being in series connection in said circuit when said unit is in said first position, said magnet coil being connected in the circuit in bridge across the signal element and the conductors, a second circuit, an electric signal element in series in the second circuit, the other one of said conductors being arranged for connection in series in the second circuit when said unit assumes its second position upon deenergization of said coil, a source of electric potential for the second circuit independent from the current source for the first circuit and a normally closed thermal switch in said second circuit designed to open in a temperature above a pre-selected normal.

2. Means for indicating current failure in a principal electric circuit, comprising an electric signal element connected in series in said circuit, a relay including a magnet coil and two parallel conductors movable as a unit between a first position in which the unit is held by the energized coil and a second position, one of said conductors being in series connection in said circuit when said unit is in said first position, said magnet coil being connected in the circuit in bridge across the signal element and the conductors, a second circuit, an electric signal element in series in the second circuit, the other one of said conductors being arranged for connection in series in the second circuit when said unit assumes its second position upon deenergization of said coil, a source of electric potential for the second circuit independent from the current source for the first circuit, a thermostatic switch connected in series with said magnet coil in bridge across the signal element and the conductors, and a normally closed thermal switch in said second circuit designed to open in a temperature above a pre-selected normal.

JOHN N. MACINNES.
